UNITED STATES PATENT OFFICE.

ERNEST B. CRUGER, OF NEW YORK, N. Y., ASSIGNOR TO HIMSELF, AND JOSEPH BRADLEY, OF BROOKLYN, NEW YORK.

APPARATUS FOR DISCHARGING DANGEROUS LIQUIDS AND GASES.

1,182,460.

Specification of Letters Patent.

Patented May 9, 1916.

Application filed July 8, 1915. Serial No. 38,813.

To all whom it may concern:

Be it known that I, ERNEST B. CRUGER, a citizen of the United States, residing in the city of New York, borough of Bronx, 5 in the county of Bronx and State of New York, have invented a certain new and useful Improvement in Apparatus for Discharging Dangerous Liquids and Gases, of which the following is a specification.

10 The object of the invention is to provide means by which dangerous liquids or gases may be led harmlessly to a place of safety in case of accident or threatened accident to the system or container in which such liquids or gases are stored or are performing 15 duties, as for example in the system of pipes and tanks or receivers constituting an ammonia refrigerating plant, and thus prevent the uncontrolled liberation of such liquids 20 and gases to the atmosphere with the consequent danger to life and property.

A further object is to provide means for facilitating and accelerating the flow of such liquids and gases to such place of safety, 25 and another important object is to provide means for initiating such flow from a safety station located at a distance from the system or container, or so situated and conditioned relatively to the latter as to be safely 30 accessible at all times.

These objects are attained by utilizing and directing the kinetic energy and the absorbent and dissolving properties of water, steam, air, or other fluid or gas, acting potentially from a head or pressure through a 35 suitable apparatus, to meet and mingle or combine with the dangerous liquid or gas and impel the latter thus mixed or absorbed to travel through a closed duct to a place of 40 harmless disposal.

The accompanying drawings form a part of this specification and show a preferred form of apparatus by which the invention may be successfully carried out.

45 Figure 1 is a diagrammatic side elevation of a refrigerating plant of the compression type, equipped with the invention. Fig. 2 is a side elevation on a larger scale and partly in vertical section, showing the safety 50 apparatus and connections therewith. Fig. 3 is a front view, partly in vertical section,

showing one form of operating device adapted to actuate the apparatus from a distant station. Fig. 4 is a vertical longitudinal section through the main portions of 55 the apparatus. Fig. 5 is a corresponding horizontal section, taken on the line 5—5 in Fig. 4. Fig. 6 is a horizontal section, on a still larger scale, showing one of the controlling valves in detail.

60 Similar letters of reference indicate the same parts in all the figures.

The invention will be described as applied to a refrigerating plant in which ammonia is employed.

65 A is the compressor, A¹ the main discharge pipe therefrom leading to the oil-trap A² and thence to the condenser A³ in which the ammonia gas is liquefied and flows to the liquid receiver A⁴. The liquid ammonia passes the expansion valve B¹ in the expansion line B and by its change from the liquid to the gaseous form absorbs heat from the cooling coils B² as usual.

70 C is the return pipe to the compressor. A break in the ammonia system immediately releases large volumes of ammonia gas extremely dangerous to life and property in the neighborhood; it is the purpose of this invention to provide means operable 75 from stations located at a distance or otherwise safely protected, by which the ammonia may be immediately drained from the system and led harmlessly away.

75 D is the body of a cored casting or valve casting having a bonnet D¹ secured thereto by bolts D² extending through lugs D³, having a passage E connected to a pipe E¹ leading from a supply of water under pressure, which may be the usual street main, not 80 shown, and a passage F connected to a pipe F¹ leading from the under side of the liquid receiver A⁴ or other convenient low point in the ammonia system.

85 G is a chamber formed in the body D, 90 preferably shaped to coact with a tapered nozzle D⁴ on the bonnet D¹, projecting into the chamber and adapted to serve therewith as an ejector.

95 G¹ is a duct leading from the chamber 100 G, connected to a pipe G² leading to a drain or sewer, not shown, or to other place or

receptacle in which ammonia may be allowed to escape safely.

Each passage E and F terminates in the body portion D in an annular valve seat 5 e, f, and the supply passage E is in communication with the chamber G through a recess E² in the bonnet and through the nozzle D⁴, while the relief passage F communicates with the chamber G exterior to 10 the nozzle, through a recess F² in the bonnet. Thus water under pressure is projected into the chamber in a strong jet and acting by the well-known ejector principle, draws ammonia in liquid or gaseous form 15 through the passage F and recess F², and combined with or absorbed by such water is forcibly ejected through the duct G¹ and pipe G² to the drain or other receptacle. The several passages, ducts, recesses and 20 nozzle are of sufficient area and so arranged and proportioned as to permit the ammonia to be drawn rapidly from the liquid receiver A⁴ when the apparatus is in operation.

The passage E is controlled by a circular 25 valve H suitably packed on both faces and has an axial valve stem H¹ extending through the bonnet D¹, terminating in a hollowed head H² serving as an abutment for one end of an expanding helical spring H³ encircling the stem and abutting at the opposite end against the outer face of the bonnet and exerting its expansive force to move the valve from its seat and open the passage E to the nozzle D⁴. The passage 30 35 F is provided with a similar valve J having a stem J¹ and head J² and equipped with a spring J³ acting in the direction to move the valve J from its seat f and permit ammonia to enter the chamber G through the 40 passage F. Both passages are held closed and the apparatus normally inactive by a yoke K pivotally attached at one end to the bonnet at the point K¹ and having its upper free end shaped to receive the hook or nose 45 L² of a latch L pivotally connected to the bonnet at the point L¹ opposite to the hinge K¹ of the yoke. The latter is drilled and tapped in axial alinement with the valve stems H¹ J¹ and receives screws K³ K⁴ 50 adapted to contact with the heads H² J² and hold the valves to their seats in opposition to the force of the springs H³ J³ when the yoke is engaged by its latch L and thus hold the passages normally closed. 55 K⁵ K⁶ are check-nuts serving to retain the screws K³ and K⁴ in position when the latter are properly adjusted. It will be seen that thus conditioned the passages E and F remain closed until the latch L is 60 lifted and the yoke K released, when by the action of the springs, aided by the pressures on the valves, the yoke will be thrown back and the valves opened. Encircling the apertures in the bonnet through which the

stems project, are valve seats d adapted 65 to receive the outer faces of the valves when the latter are released, and prevent leakage of water or ammonia through such apertures.

The latch may be operated by a variety 70 of means; that shown in the drawings consists of a housing N mounted upon the case M in which the yoke and latch are inclosed for protection against accidental release, having passages therein connected to conduits N¹ which extend to locations or stations remote from the ammonia system or so protected as to be safely approached, and contain each a light cable or flexible cord attached at one end to the latch and terminating 75 in any suitable device for exerting a strong pull on the latch, as for example, the winding-drum N³ inclosed in a casing N⁴ and rotated by a lever N⁵ through a slot n in the casing. 80 85

In the event of fire in cold storage warehouses or refrigerating plants, the possibility of a break in the ammonia system and consequent liberation of ammonia gas constitutes a serious menace to the firemen 90 and others in and about the building. This invention permits the ammonia to be drawn off safely and quickly before such break occurs, or in the event of a break the latch may be tripped from any of a number of 95 stations about the plant and safely located in respect to the ammonia fumes, and a large part of the ammonia led harmlessly away.

Although the invention is described as 100 applied to an ammonia plant, it will be understood that it will serve successfully in controlling other dangerous, noxious, explosive, or inflammable liquids and gases; and other fluids having the property of absorbing, dissolving, neutralizing, or combining with such liquids or gases, may be substituted for water as a vehicle for inducing the flow and carrying away the dangerous liquids or gases. 105 110

Other means than that shown may be employed for lifting the latch and releasing the yoke, and the arrangement of passages, pipes and conduits may be varied as circumstances may dictate. 115

E³ and F³ are check-valves in the pipes E¹ and F¹ serving to prevent back flow through such pipes due to excess pressure in either.

I claim:—

1. In an apparatus of the character set forth, a valve casing having a chamber therein, a relief passage leading to said chamber and connected to the system to be emptied, a supply passage leading to said chamber and arranged to deliver fluid under pressure thereto, a discharge duct from said chamber, valves controlling said passages 125

125

and held normally closed, and means operable from a safety station for opening said valves.

2. In an apparatus of the character set forth, a valve casing having a chamber therein, a relief passage leading to said chamber and connected to the system to be emptied, a supply passage leading to said chamber and arranged to deliver fluid under pressure thereto, a discharge duct from said chamber, valves controlling said passages, means for holding said valves normally closed, and means operable from a safety station for releasing said valves.

15 3. In an apparatus of the character set forth, a valve casing having a chamber, an ejector nozzle in said chamber, a relief passage leading to said chamber exterior to said nozzle and connected to the system to be emptied, a supply passage leading to said chamber through said nozzle and arranged to deliver fluid under pressure thereto, a discharge duct from said chamber, valves controlling said passages, and means operable from a safety station for releasing said valves.

4. A valve casing having a chamber therein, a relief passage leading to said chamber and connected to the system to be emptied, a supply passage leading to said chamber and arranged to deliver fluid under pressure thereto, a discharge duct from said chamber, valves controlling said passages, springs tending to open said valves, a yoke adapted to hold said valves closed in opposition to said springs, and a latch for holding said yoke in the closed position.

5. A valve casing having a chamber therein, a relief passage leading to said chamber and connected to the system to be emptied, a supply passage leading to said chamber and arranged to deliver fluid under pressure thereto, a discharge duct from said chamber, valves controlling said passages, springs tending to open said valves, a yoke adapted to hold said valves closed in opposition to said springs, a latch for holding said yoke in the closed position, and means operable from a safety station for moving said latch to release said yoke.

6. A valve casing having a chamber therein, a relief passage leading to said chamber and connected to the system to be emptied, a supply passage leading to said chamber and arranged to deliver fluid under pressure thereto, a discharge duct from said chamber, valves controlling said passages, springs tending to open said valves, a yoke adapted to hold said valves closed in opposition to said springs, a latch for holding said yoke in the closed position, a plurality of winding-drums each located in separate safety stations, and connections from said drums to said latch, whereby the rotation of

either drum moves said latch to release said yoke.

7. A valve casing comprising a body and bonnet, a chamber in said body, a relief passage in said body communicating through said bonnet with said chamber and arranged to be connected to the system to be emptied, a supply passage in said body communicating through said bonnet with said chamber and arranged to deliver fluid under pressure to said chamber, a discharge duct from the latter, a relief valve seat and a supply valve seat on said body, axially movable double-faced valves coacting with said valve seats to close said passages, axial valve stems on said valves extending through apertures in said bonnet, springs tending to move said valves to open said passages, and valve seats on said bonnet surrounding said apertures and stems, adapted to coact with said valves and close said apertures by the action of said springs in moving said valves to open said passages.

8. A valve casing comprising a body and bonnet, a chamber in said body, an ejector nozzle on said bonnet extending into said chamber, a relief passage in said body communicating through said bonnet with said chamber exterior to said nozzle and arranged to be connected to the system to be emptied, a supply passage in said body communicating through said bonnet with said chamber through the interior of said nozzle and arranged to deliver fluid under pressure to said chamber, a discharge duct from the latter, axially movable valves controlling said passages and having stems extending through said bonnet, heads on said stems, and springs between said heads and bonnet tending to move said valves to open said passages, a yoke hinged at one end to said bonnet, means on said yoke for engaging said heads, and a movable latch arranged to engage the free end of said yoke and hold said valves closed in opposition to said springs.

9. A valve casing comprising a body and bonnet, a chamber in said body, an ejector nozzle on said bonnet extending into said chamber, a relief passage in said body communicating through said bonnet with said chamber exterior to said nozzle and arranged to be connected to the system to be emptied, a supply passage in said body communicating through said bonnet with said chamber through the interior of said nozzle and arranged to deliver fluid under pressure to said chamber, a discharge duct from the latter, axially movable valves controlling said passages and having stems extending through said bonnet, heads on said stems and springs between said heads and bonnet tending to move said valves to open said passages, a yoke hinged at one end to said

bonnet, means on said yoke for engaging said heads, a movable latch arranged to engage the free end of said yoke and hold said valves closed in opposition to said springs, 5 and means operable from a safety station for moving said latch and releasing said yoke and valves.

In testimony that I claim the invention above set forth I affix my signature, in presence of two witnessse.
